(57) **CLAIM**

The ornamental design for a truss spacer, as shown and described.

DESCRIPTION

FIG. 1 is a top perspective view of the truss spacer showing my new design.

FIG. 2 is an enlarged perspective view of the encircled portion of FIG. 1 showing one end of the truss spacer generally from above, and also serves as a perspective view of the other end of the truss spacer.

FIG. 3 is an enlarged top plan view of the truss spacer with a central portion of the truss spacer broken away.

FIG. 4 is an enlarged bottom plan view of the truss spacer with the central portion of the truss spacer broken away.

FIG. 5 is an enlarged side elevational view of the truss spacer with the central portion of the truss spacer broken away.

FIG. 6 is an end elevational view of the truss spacer which is taken on line 6-6 of FIG. 5 and serves as the end elevational view taken from either end of the truss spacer.

FIG. 7 is a sectional view of the truss spacer taken on line 7-7 of FIG. 5.

FIG. 8 is a sectional view of the truss spacer taken on line 8-8 of FIG. 5; and,

FIG. 9 is a sectional view of the truss spacer taken on line 9-9 of FIG. 5.

The broken line showing of the rectangular opening is included for the purpose of illustrating portions of the truss spacer and forms no part of the claimed design.
